UNITED STATES PATENT OFFICE.

BLAIR A. ESTEP, OF SOUTH BEND, INDIANA.

ATTACHMENT FOR STEAM-BOILERS.

No. 846,100.

Specification of Letters Patent.

Patented March 5, 1907.

Application filed June 22, 1905. Serial No. 266,392.

To all whom it may concern:

Be it known that I, BLAIR A. ESTEP, a citizen of the United States, residing at South Bend, in the county of St. Joseph and State of Indiana, have invented new and useful Improvements in Attachments for Steam-Boilers, of which the following is a specification.

This invention relates to an attachment for a steam-boiler, and has for its object to provide apparatus for charging a boiler with a boiler compound and for regulating the feed of such compound to the boiler.

For a full understanding of the construction, merits, and advantages of my invention reference is to be had to the following description and to the accompanying drawing, which illustrates the feeding apparatus by a view in longitudinal vertical section.

Making renewed reference to the drawing, 1 designates a boiler feed-pipe, which leads from a pump or injector and connects at the end 2 with a boiler. (Not shown.) This pipe is preferably made in sections by interposing suitable couplings 3 and 4 between the ends of several pipe-sections, although these couplings may be dispensed with and the pipe 1 tapped in several places.

5 designates a tank or reservoir into which the liquid boiler compound is introduced, as by removing the screw-plug 6 at the top. From the lower end of this tank extends an intake-pipe 7, in which is a suitable stop-cock 8. The end of the pipe is threaded and 35 screwed within the coupling 3, although it may be screwed directly within the pipe 1. Its lower end 9 projects a considerable distance within the feed-pipe and is preferably cut at an angle, so as to provide a take-up 40 for some of the water passing through the feed-pipe, as indicated by the arrows in the drawing.

From near the top of the reservoir 5 extends an escape-pipe 10. This pipe has a 45 suitable valve 11, and its lower end is fitted into the coupling 4 and projects into the feed-pipe 1, being preferably cut so as to deliver the boiler-compound into the feed-pipe, but not take up any of the water passing through 50 the pipe, as indicated by the arrows.

When the reservoir 5 has been filled with a suitable liquid boiler compound, some of the water passing through the feed-pipe 1 will

enter the reservoir 5 through the intake-pipe 7, the opening of which faces in a direction 55 opposite to the flow of the water through the feed-pipe to receive the impact of the water therein, causing some of the water flowing through the feed-pipe to enter the said intake-pipe 7 and force the compound in the 60 reservoir 5 out through the escape-pipe 10 and down to the feed-pipe again, where it is carried forward by the force of the water which escapes past the take-up end 9 of the intake-pipe, the opening of the escape-pipe 65 10 being turned in the direction of the flow of the water, so as not to receive the impact thereof. Thus it will be seen that there is an injection action at the take-up end of the intake-pipe and an ejection action at the delivery end of the escape-pipe 10. A valve 8 may regulate the flow of water into the reservoir, and the valve 11 may regulate the discharge of the compound from the reservoir, while the water in the reservoir may be 75 drawn off through the petcock 12.

Having thus described my invention, what I claim, and desire to secure by Letters Patent, is—

In an apparatus of the class described, the 80 combination with the boiler feed-pipe, and the reservoir, of means for forcing a boiler compound from the reservoir by the flow of water through the feed-pipe, comprising an intake-pipe communicating with the bottom 85 of the reservoir and with the feed-pipe and having its end that enters the feed-pipe cut obliquely with its opening facing in a direction opposite to the flow of the water, whereby an injection action is provided, an escape-pipe 90 connected with the reservoir near the upper end thereof and with the feed-pipe in the rear of the intake-pipe and having its end that enters the feed-pipe cut obliquely with the opening facing in the direction of the flow 95 of the water, whereby an ejection action is provided, and valves in the intake and escape pipes for controlling the flow of material therethrough.

In testimony whereof I affix my signature 100 in presence of two subscribing witnesses.

BLAIR A. ESTEP.
